METHOD FOR BENDING TUBES USING
A CONGEALABLE MATERIAL
Joseph M. Kelrick, New York, N.Y.
(4 Hawthorne Lane, Lawrence, N.Y. 11559)
Filed July 23, 1965, Ser. No. 474,429
9 Claims. (Cl. 29—423)

ABSTRACT OF THE DISCLOSURE

Method for preparing a tube for bending, wherein the tube is submerged in and filled with congealable material, closed at both ends, and then removed from the body of congealable material.

This invention has to do with the pre-treatment or preparation of hollow tubing for bending.

The bending or other working of tubing or the like has long been a problem since the tubing will collapse at the bend, thereby weakening the tube, blocking the internal passage, and materially affecting its aesthetic appearance. Hence, various filler materials have been inserted in the tubing prior to bending in an attempt to avoid such result; for example, sand, cement and sawdust. Such materials may be easily and quickly poured into tubing of a substantial diameter but not into tubing of a small diameter; e.g., $\frac{1}{4}$ inch and smaller.

Therefore, it is an object of the present invention to provide a method for preparing a section of hollow tubing for bending or the like and, in particular, hollow tubing of a small diameter.

Another object of the present invention resides in the provision of a method for preparing a section of hollow tubing for bending which enables the prepared tube to be bent to the desired configuration without distortion or collapse.

A further object of the present invention resides in the provision of a method for preparing a section of hollow tubing for bending which is simple in execution, positive in action, and commercially feasible.

A still further object of the present invention resides in the provision of an apparatus for carrying out the method for preparing a section of hollow tubing for bending which produces a complete filling of the section with a congealed material.

Other objects and advantages will become apparent from the following description taken in conjunction with the accompanying drawings, in which:

FIGURES 1 to 5 graphically illustrate the steps of the method for preparing a section of hollow tubing for bending according to the present invention.

FIGURES 6 to 9 graphically illustrate the steps for bending the prepared tubing to the desired configuration.

FIGURE 10 is an elevational front view of the apparatus employed in carrying out the method according to the present invention.

FIGURE 11 is a side view of the assembly of FIGURE 10.

FIGURE 12 is a fragmentary sectional view taken on the line 12—12 of FIGURE 10.

FIGURE 13 is a fragmentary sectional view taken on the line 13—13 of FIGURE 10.

Referring to FIGURES 10 to 13 of the drawings, the numeral 10 designates, generally, the treating apparatus employed in carrying out the method for preparing a section of hollow tubing for bending according to the present invention, such apparatus comprising an elongated hollow receptacle 12 which is closed at one end 14 and which is open at the opposite end 16. The wall of the

2

receptacle 12 is provided with a transverse slot 18 which is spaced from and is adjacent the closed end 14 of the receptacle 12. A resilient rest 17 in the form of a rubber cushion pad or the like is disposed within the receptacle 12 inwardly of the closed end 14 and which partially projects above the lower edge 18' of the slot 18. A handle 19 is on the receptacle 12 at the upper end thereof for facilitating manual handling of the apparatus.

The treating apparatus also includes an elongated plug 20 which is conformably shaped to fit within the upper end portion of the receptacle 12. The plug 20 is insertable into and withdrawable out of the open end 16 of the receptacle 12. The plug has a socket 21 extending inwardly from its lower end which slidably receives the stem 23 of the plunger 25. Circumposed about the stem 23 is a coil spring 27 which biases the head 29 of the plunger 25 away from the plug 20 and into snug engagement with the adjacent upper end of the tubing 30, as shown in FIGURE 12. The plunger 25 is made captive in the socket 21 by a pin 31, which is mounted interiorly of and extends transversely across the receptacle 12 through the slot 33 in the stem 23. Interengaging means on the plug 20 and the wall of the receptacle 12 serves to releasably hold the plug in position in the receptacle 12. Specifically, this means embodies a spring latch element 22 on the plug 20 which releasably engages in one of the air holes or apertures 24 formed in the wall of the receptacle 12 inwardly of and adjacent the open end 16.

In carrying out the method of the present invention, a section of hollow tubing to be bent, and indicated by the numeral 30, FIGURE 1, is selected. This tubing 30 is completely immersed in an oil bath 32, FIGURE 2, to a temperature within the range of 200 to 250° Fahrenheit. Specifically, the tube 30 is placed in a basket 34 which is supported in an insulated open top vessel 36 containing a bath of light mineral oil, the cage being provided with a handle 38 for inserting and supporting the tube 30 in the bath 32 and for withdrawing the treated tubing from the bath 32. The vessel 36 has a conventional electrical heating element 33 embedded in suitable insulation 35, such as Fiberglas. The immersion of the tubing 30 in the bath 32 pre-heats the tubing 30 to the temperature at which it will readily receive a congealable or solidifiable material in a flowable state without causing congealing of such flowable material upon contact with the tubing 30, while the oil lubricates the tubing 30 with a film which will exist between the congealable material in a flowable state and the inner surface of the tubing and thus prevent subsequent tinning.

A body of congealable or solidifiable material in a flowable state is provided. This body is contained in an open top insulated container 40, FIGURE 3, having a conventional heating element 41 embedded in an appropriate insulation, for example, Fiberglas. The congealable material is an alloy 42 which has a low temperature boiling point. The alloy employed is known by the trademark "Cerrobend," consisting of 50% bismuth, 26.7% lead, 13.3% tin, and 10% cadmium, and has a melting point of 158° Fahrenheit. The body of congealable material or alloy 42 in a flowable state which is contained in the container 40 is maintained at a temperature above its melting point of 158° Fahrenheit, or at a temperature of approximately 250° Fahrenheit.

The treating apparatus 10 is first placed in the heated oil bath 32 and permitted to reach the temperature of the bath, FIGURE 2. Then, it is removed and submerged in an upstanding position in the body or alloy 42, FIGURE 3, with the closed end 14 of the receptacle 12 and the slot 18 below the level of the body or alloy 42. The alloy 42 will enter the slot 18 and fill the receptacle 12 to the level of the alloy in the container 40.

With the treating apparatus in position within the body or alloy 42 and its receptacle 12 fully charged with the alloy 42, the basket 34 carrying the oil-treated tubing 30 is manually removed from the bath 32 and the basket 34 held for a time sufficient to permit draining of excess oil from the tubing 30, whereupon the drained tubing 30 is lifted out of the basket 34 by means of a suitable lifting tool or tweezers, inserted through the open top 16 of the receptacle 12 of the treating apparatus 10, FIGURE 3, and the lifting tool or tweezers released, thus permitting the tubing 30 to descend by gravity within the receptacle 12 and engage the rest 17. During such descent, the alloy 42 will enter the open lower end of the tubing 30 and completely fill the section of the tubing 30 with the alloy 42 from the bottom of the top. At this point, the plug 20 is inserted through the open top 16 of the receptacle 12 until the head 29 of the plunger 25 forcibly engages and closes the upper end of the filled section of tubing 30 while the lower end of the tubing is urged against and closed by the rest 17 to thereby retain the flowable material or alloy in the tubing. When the plug 20 has been fully inserted into the receptacle 12, the latch element 22 is caused to interengage one of the apertures 24 to thereby releasably hold the plug 20 in position within the receptacle 12, as seen in FIGURE 12.

After the tubing 20 is fully filled with the alloy 42 and the plug 20 is in latched position, the receptacle 12 is next quickly withdrawn from the alloy or body 42 and promptly placed in an upright position in a cold bath of mineral oil. As the receptacle is withdrawn, the excess alloy surrounding the tubing 30 drains out through the slot 18 into the container 40. The mineral oil is contained in an open top tank 50, FIGURE 4, and the oil is chilled preferably by means of cold water circulating through the water jacket 52 provided on the tank. This treating apparatus assembly is permitted to remain in the tank 50 for a short interval of time, resulting in the chilling of the alloy 42 contained in the tubing 30 to a temperature below its melting point such as to cause the alloy to congeal to solid form.

After such chilling is completed, the treating apparatus assembly is withdrawn from the tank 50, the latch element 22 released, the plug 20 withdrawn, followed by the withdrawal of the tubing 30 filled with congealed alloy 42 in solid form. The tubing 30 filled with the congealed alloy 42 in solid form is graphically illustrated in FIGURE 5.

The filled tubing 30 is then placed in any suitable bending device, such as that designated by the numeral 60 in FIGURE 6, and bent to the desired configuration, in this case, a split ring 62, as illustrated in FIGURE 7. The alloy 42 is then removed in any conventional manner, such as by placing the split ring in a heated oil bath 66, FIGURE 9, wherein it is permitted to remain for a sufficient interval of time to thereby convert the congealed alloy to a flowable state and be discharged through the split into the bath and deposited as a separate layer 64 on the bottom of the bath, as shown in FIGURE 9. If desired, conventional agitation or tumbling means may be applied to the ring to insure complete removal of the molten alloy.

The thus obtained hollow split ring 62 is then treated so as to produce a completely formed and sealed ring.

The tubing 30 filled with congealed alloy 42 in solid form lends itself to any bending operation, and produces a symmetrical bent article without distortion or collapse in any part thereof.

What is claimed is:

1. The method of preparing a section of hollow tubing for bending which comprises providing a body of congealable material in a flowable state, providing a treating apparatus embodying an elongated receptacle closed at one end and open at the opposite end with an opening formed in the side wall adjacent the closed end and having a resilient rest adjacent its closed end, submerging said

receptacle in an upstanding position in said body with the closed end and the opening below the level of the body and the open end projecting above the level of the body, continuing the submersion of said receptacle in said body until the flowable material has flowed through the opening of said receptacle and filled the receptacle to substantially the level of the body, inserting a section of hollow tubing through the open top of the receptacle and permitting it to descend within the receptacle to thereby completely fill the section of tubing with the flowable material from the bottom to the top, inserting a plug through the open end of said receptacle until it engages and closes the upper end of the filled section of tubing to thereby retain the flowable material in said tubing, withdrawing the plugged receptacle from said body, cooling the plugged receptacle to thereby cause the flowable material to congeal to solid form, and recovering the section of tubing filled with the congealed material in solid form.

2. The method according to claim 1, wherein the congealable material is an alloy having a low temperature melting point, and heated above said melting point.

3. The method according to claim 1, wherein the congealable material is an alloy of 50% bismuth, 26.7% lead, 13.3% tin, and 10% cadmium, having a low temperature melting point of 158° Fahrenheit, and heated above said melting point.

4. The method according to claim 1, wherein the section of hollow tubing prior to the insertion in said receptacle is coated with a film of oil.

5. The method according to claim 1 wherein the section of hollow tubing prior to the insertion in said receptacle is heated.

6. The method according to claim 1 wherein the receptacle is coated with a film of oil prior to being submerged.

7. The method according to claim 1 wherein the receptacle is heated prior to being submerged.

8. The method of filling tubing with congealable material which comprises:

(a) providing an elongated receptacle open at one end and closed at the other end with an opening formed in the side wall adjacent the closed end,

(b) submerging the closed end of said receptacle in a body of congealable material in a flowable state to permit said material to enter said receptacle through said opening and fill the submerged portion of said receptacle,

(c) inserting tubing to be filled through the open end of said receptacle and permitting said tubing to descend until one end abuts the closed end of the receptacle, thereby filling the tubing with the flowable material,

(d) and inserting plug means through the open end of said receptacle and forcibly engaging and closing the proximate end of the tubing while forcing the distal end of the tubing against the closed end of said receptacle to close the distal end of the tubing.

9. The method of filling tubing with congealable material which comprises:

(a) providing an elongated receptacle open at one end and closed at the other end with an opening formed in the side wall adjacent the closed end,

(b) submerging the closed end of said receptacle in a body of congealable material in a flowable state to permit said material to enter said receptacle through said opening and fill the submerged portion of said receptacle,

(c) inserting tubing to be filled through the open end of said receptacle until one end abuts the closed end of the receptacle, thereby filling the tubing with the flowable material,

(d) and inserting plug means through the open end of said receptacle and forcibly engaging and closing the proximate end of the tubing while forcing the distal

end of the tubing against the closed end of said receptacle to close the distal end of the tubing.
